IRON

Julius K. Sebo, Staten Island, N. Y., assignor to
 American Plush & Velvet Pressboard Co. Inc.,
 New York, N. Y., a corporation of New York

Application July 15, 1938, Serial No. 219,327

6 Claims. (Cl. 68—222)

This invention relates to irons of the type for steaming, glazing or ironing furs and other materials requiring such treatment.

It has been suggested to generate steam in an iron or to supply steam to it and discharge some of the steam through perforations in the bottom of the iron. An objection to this proposal has been the discharge of a quantity of water onto the work both during operation of the iron and in starting because there is substantial condensation.

An object of this invention has been to eliminate this disadvantage and preclude an objectionable amount of water reaching the work.

Another object has been to superheat the steam in the iron so that dry steam is delivered to the work.

Yet another object is to provide an absorbent material for any condensed steam to reduce the danger of its reaching the work in objectionable quantity.

A further object is to provide a finely perforate medium such as a pressing cloth or its equivalent carried by the iron and through which steam is distributed over the work in a satisfactory manner.

Specifically, dry steam is spread through a removable supporting frame over which a woven flexible fabric, like canvas, is stretched so that the steam passes through the interstices between the warp and weft threads and onto the work. Any condensed moisture is absorbed in the fabric.

Referring to the drawing

Fig. 1 illustrates one embodiment of this invention.

Fig. 2 is a bottom plan view of the device of Fig. 1 with parts of the fabric and its supporting frame broken away.

Fig. 3 is a top plan view of the iron of Fig. 1 with the casing removed and parts broken away.

Fig. 4 is a section on the line 4—4 of Fig. 1.

Fig. 5 illustrates another embodiment of this invention as viewed from the bottom with the parts broken away.

The iron illustrated includes a lower portion 10, preferably a casting of aluminum. In fact most of the iron is made with aluminum in order to be light in weight since it is more often held in the hand and used in substantially vertical position. An upper portion 11 is preferably of the same material and between these portions there is an electric heater 12 comprising resistance wire 13 placed between or around sheets of mica 14. A casing 15 of plated thin sheet metal is provided with a handle 16 and is

clamped over the upper part contiguous the lower portion 10. The lower portion 10 is provided with a hollow space 17 extending entirely around the central recessed portion shown in Fig. 1.

Steam is supplied to the rear of the lower portion, passes around the hollow space 17 to the perforate bolt or other securing means 18 and into the hollow space 18 of the upper portion 11. The steam circulates through the upper portion as shown in Figs. 1 and 3 and then passes out and downwardly through the hollow bolt or other fastening means 18 into a space 21 below the lower portion 10 and above a bottom frame over which a woven fabric material is placed. Steam issuing from the securing means 18 strikes the deflector or distributor plate 22 for the purpose of spreading it forwardly and laterally. A flexible tube leading from some type of steam generator is connected to the nipple 23 and leads into and around the lower portion of the iron. Since the iron is frequently held in a substantially vertical position any condensed steam is returned to the boiler or other generator through the outlet 24 by another flexible connection not shown. In passing through the iron the steam is superheated by contact with the walls, especially the upper wall in the lower portion and with the walls of the upper portion by reason of these walls being heated from the resistance wire 13 placed between them. The heat imparted to the steam by this heating element is sufficient to slightly superheat or make the steam dry, yet not enough to substantially raise the pressure of the steam as otherwise the superheated steam might flow back through the condensation return 24 which of course is not intended.

Secured beneath the lower portion 10 is a frame 25 and over this frame is stretched a woven fabric material like canvas 26. The frame includes the cast aluminum member 27 provided therein with a large number of perforations 28 through which the steam may pass. Projecting outwardly from the body portion of the frame are a number of projections 29 which serve as abutments for a metal mesh 30, the mesh serving as an abutment for the fabric between the projections 29. To increase the thickness of the fabric and provide an excellent inner absorptive surface, a layer of soft flannel 31 is placed between the mesh 30 and the canvas 26. The frame has an upwardly extending boss 32 threaded to receive the supporting and clamping screw 33 having a head which is received and held by a threaded sleeve 34 passing

through the casing 15, through the upper portion 11 and threaded into the lower portion 10. The threads of the screw 33 do not engage the sleeve 34. A cap 35 is threaded over the enlarged head of the sleeve 34.

5 The hollow bolts 19 and 20 are made accessible for insertion and replacement by having the upper wall of the upper portion 11 provided with large enough perforations to insert 10 a socket wrench and these perforations are closed by threaded caps 36 and 37, which may be held in place by white lead or other means to prevent escape of steam.

15 When the frame 25 is securely held by tightening the screw 33 it will be seen in Fig. 1 that the frame and canvas are contiguous the lower edges of the lower portion 10, these edges serving to clamp the fabric at 38 to the frame.

20 In Fig. 5 the frame and fabric bottom portion 20 do not extend over the entire lower surface of the iron as is the case in Figs. 1 and 2 but are of smaller area countersunk within a recess 39 of the bottom of the iron so that the fabric 40 covering its supporting frame may be substantially 25 flush or on a level with the edge portions 41 which are of polished metal. The edge portions 41 not being covered with canvas are adapted to perform an ordinary ironing operation while the fabric and frame serve to distribute moisture. The 30 construction of the type shown in Fig. 5 is believed to be better adapted to perform any one of an ironing, steaming, or glazing operation than the device of Figs. 1 and 2. As shown in Fig. 2 since the fabric covers the entire lower surface of 35 the iron this construction is not as well adapted for ironing as is that of Fig. 5 but is suitable for steaming and glazing. The supporting frame for the fabric in Fig. 5 is of the same general construction and possesses the same means of attachment as is shown in Figs. 1 and 2. The rest 40 of the iron is the same as that shown in Fig. 1. There is a ledge 42 against which the frame and fabric are clamped.

45 Among the advantages of this invention may be mentioned the lessened danger of water getting onto the goods since the steam is dry and slightly superheated. Any moisture which might collect on the work by reason of its being colder than the steam should be absorbed by the fabric bottom portion. In one aspect this invention may be regarded as the provision of an iron with which no ordinary pressing cloth is needed since such cloth or its equivalent is carried by the iron itself. Care is to be taken in seeing that the electric 50 heater does not raise the temperature of the steam and its pressure enough to cause any substantial loss of dry steam through the condensation return pipe 24. Devices of the type illustrated use only about one and one-half (1½) 55 gallons of water an hour during operation.

60 I claim:

1. The combination with an iron, of an electric heater therein, tortuous fluid passages around said heater, a removable pressing-cloth supporting frame in the bottom of the iron to which the heated fluid is delivered, and fastening means for said frame passing through the iron and accessible from the top of the iron for removal of said frame.

2. An iron including a woven fabric cloth covering only a portion of the bottom portion of the iron, a supporting frame for said cloth countersunk into the bottom of the iron to have the cloth substantially flush with the portion of the bottom over which the cloth does not extend, and means for supplying steam from within the iron to and through said cloth. 5

3. An iron adapted for steaming or glazing furs and the like comprising a steam supply pipe 10 leading to the iron from an outside source of steam, an outlet for water of condensation by gravity from the iron and leading back to the source of steam supply, a tortuous passage for the steam within the iron, an electric heater for 15 superheating the steam within the iron, a finely perforate moisture absorbent fabric on the bottom of the iron, means for distributing the heated steam over said fabric so that it may pass to the work, the size of said heater being such that the 20 steam is substantially dried out and superheated slightly whereby to avoid any substantial increase in pressure of steam in the iron causing loss of steam out the water outlet and avoid the necessity for a safety valve in the iron. 25

4. An iron including a body portion, a heater therein, means for supplying fluid to the iron, a perforate bottom plate, an absorbent fabric extending over the perforate portion of said plate, means for clamping said plate to the body portion 30 of said iron and also clamping edge portions of said fabric between the said plate and the body portion of said iron to hold the fabric in place.

5. An iron containing a steam receiving chamber, a heater contiguous said chamber, means for 35 emitting steam from said chamber and superheating the same after leaving said chamber, a fabric covered bottom portion through which superheated steam may be supplied to the goods being treated, a steam supply pipe connected to the 40 rear portion of said chamber, an outlet pipe also connected to the rear portion of said chamber and laterally spaced from said supply pipe, said superheating means being adapted for only slight heating whereby no valves are required in said 45 iron and no excessive loss of superheated steam occurs out the steam outlet pipe.

6. A pressing iron comprising a central body portion having a central steam chamber with an inlet and an outlet, an upper body member having an upper steam chamber, an electric heater mounted between said body members, a frame member having a perforated bottom secured beneath said central body member, said central body member and said frame member having a 55 lower steam chamber between them, tubular members securing said body members together, one of said tubular members providing a passage for steam to pass from the central body steam chamber to the upper steam chamber and the 60 other tubular member providing a passage for steam to pass from the upper steam chamber to the lower steam chamber, and means for securing a fabric facing beneath the perforated frame member around the edges thereof. 65
